UNITED STATES PATENT OFFICE

150,201

DESIGN FOR AN ELECTRICALLY OPERATED
HAIR BRUSH OR THE LIKE

Arthur R. Botham, Great Barrington, Mass.

Application January 13, 1947, Serial No. 136,119

Term of patent 3½ years

(Cl. D86—10)

To all whom it may concern:

Be it known that I, Arthur R. Botham, a citizen of the United States, residing at Great Barrington, county of Berkshire and State of Massachusetts, have invented a new, original, and ornamental Design for an Electrically Operated Hair Brush or the Like, of which the following is a specification, reference being had to the accompanying drawing, forming a part thereof.

In said drawing:

Fig. 1 is a perspective view of an electrically operated hair brush or the like showing my design.

Fig. 2 is a plan view of the same; and
Fig. 3 is an end elevation of the same.

I claim:

The ornamental design for an electrically operated hair brush or the like, substantially as shown.

ARTHUR R. BOTHAM.
